ATTACHMENT FOR PRINTING PRESSES

Charles Grillo, Brooklyn, N. Y.

Application May 6, 1933, Serial No. 669,684

8 Claims. (Cl. 101—250)

This invention relates to improvements in printing presses and more particularly it pertains to a new control mechanism for printing presses which mechanism will function to effect

5 an automatic stopping of a printing press under certain predetermined operating conditions.

In certain types of printing presses, particularly of the type wherein a type bed and a rotating cylinder are reciprocated in opposite directions to effect a printing operation, it is highly important that these movements maintain a definite and fixed relation to one another and unless this relation is maintained, a successful printing operation cannot be had.

10 It is one object of the present invention to improve the construction and mode of operation of printing machines of the afore-mentioned type and to provide such machines with mechanism which will effect a better printing operation than prior machines.

15 In machines of the general type mentioned, the cylinder is rotated during its reciprocating movement in one direction while during its reciprocating movement in the opposite direction, the cylinder is at rest so far as rotation is concerned. This operation requires that the cylinder be connected and disconnected with its driving means at proper intervals to produce the desired result.

20 A feature of the present invention resides in a novel control mechanism for automatically disconnecting the power and thereby stopping the machine, if the cylinder fails to rotate when it is reciprocating in that direction in which it should also rotate.

25 Another feature of the invention resides in a device which is simple in its construction and operation and which is capable of attachment to machines which at present have certain other control mechanisms, without altering or effecting in any manner, those control mechanisms with which such machines may be provided.

30 Still another feature resides in a novel type of control which will operate independently of any controlling mechanisms with which a machine may be equipped.

35 Other features of the invention relate to certain novel and improved constructions, arrangements and combinations of parts hereinafter described and particularly pointed out in the claims, the advantages of which will be readily understood and appreciated by those skilled in the art.

40 The invention will be clearly understood from the accompanying drawing illustrating the in-

vention in its preferred form, and the following detailed description of the constructions therein shown.

In the drawing,

Figure 1 is a fragmentary perspective view of a printing press of the reciprocating bed and cylinder type showing an attachment constructed in accordance with the present invention, applied thereto,

Figure 2 is a fragmentary view in end elevation thereof,

Figure 3 is a fragmentary top plan view of a portion thereof,

Figure 4 is a detail end elevation looking in the opposite direction to Figure 2, and;

Figure 5 is a vertical sectional view taken substantially on the line 5—5 of Figure 4.

I have chosen to illustrate my invention in a reciprocating bed and cylinder printing press of the vertical type. In the drawing, the reference numeral 10 designates the frame of the machine, 11 the cylinder, and 12 a portion of the reciprocating cylinder carriage. The power for driving the press is not shown, but the press is connected and disconnected with its power by means of a lever, the upper portion 13 of which is illustrated in Figure 1. This lever has a portion 14 which is received within a notch 15 of one arm of the bell crank lever 16, the other arm 17 carrying an automatic stop latch 18, the bell crank lever being pivoted upon a bolt or the like 19 attached to the frame 10 of the press. So far as described, the parts are of conventional construction and are so arranged that when a trip engages the automatic stop latch 18, the power will be disconnected and the printing press will be stopped.

These printing presses have a control mechanism of the general type illustrated in Patent Number 1,582,576, April 27, 1926, which mechanism includes a pneumatic cylinder 21 within which reciprocates a piston, not shown, the rod 22 of which is adapted to be projected to a point where it will engage the automatic stop latch 18 to trip the same under certain operating conditions. Leading from the cylinder 21 there is a suitable pipe 23 connected to a vacuum mechanism not shown. This control mechanism is adapted to stop the printing press when certain conditions exist upon the transfer table and as long as the vacuum system is open, the piston will be retracted where its rod 22 cannot engage the automatic stop latch 18. However, when the vacuum system is closed, the vacuum operates to project the piston 22 to a point where it will

engage the automatic stop latch 18 and stop the machine. These parts, like those before mentioned, are of conventional design and construction.

5 In machines of this type the type bed and cylinder move in opposite directions to produce a printing operation, the cylinder rotating during the printing operation. When movable in the other direction, however, the cylinder does not rotate. This action of the several parts requires that the cylinder be connected and disconnected from its driving mechanism, not shown, at properly timed intervals and in the operation of such machines it does not always happen that this 10 action takes place due to various reasons known to operators of these machines. The pneumatic control mechanism heretofore described does not take care of this situation and it often happens that the printing press is subjected to serious 15 injury because of this fact.

20 The present control mechanism is of the mechanical type and is adapted to effect a stopping of the machine in case the cylinder 11 thereof does not for any reason rotate during the interval when it should be rotating.

25 The control mechanism herein is mounted upon the reciprocating cylinder carriage and consists of a plate 30 having a central opening 31 which plate is adapted to be attached to the outer end of the pneumatic cylinder 21 with which certain of said presses are already equipped by means of bolts or the like 32. These bolts 32 engage in openings already provided in the end of the cylinder 21. The plate 30 has an extension 33 and projecting inwardly therefrom there is a bearing 34 which occupies a position substantially parallel with the pneumatic cylinder 21. Mounted within this bearing 34 there is a trip member 35 having a right angular outer end 36. Carried by the inner end there is a dog or the like 37 which has a cut out portion 38 and this dog is so positioned that it will be closely adjacent the end of the cylinder 11. The cut out portion 38 receives a screw or the like 39 carried by the trip member 35 and this cut out portion 40 and screw 39 permit of a free movement of the dog 37 in one direction but will rotate the trip member 35 when the dog is moved in the opposite direction. For example, the dog 37 may move upwardly as shown in dotted lines in Figure 4 without effecting a rotating movement of the trip member 35. In moving downwardly, however, the wall 41 of the cut out portion 38 will engage the screw 39 and effect a rocking of the trip member 35 to move its right angular end 36 from its normal horizontal position in which it is shown in dotted lines in Figure 1 to the position in which it is shown in full lines in Figure 1.

50 The reference numeral 45 designates a member attached to the end of the cylinder 11 and said member has a head 46 provided with a curved outer edge 47. The parts are so assembled that the member 45, when the cylinder 11 is rotated will engage the dog 37 and will rock the right angular end 36 of the trip member to the full line position in which it is shown in Figure 1. In this full line position the right angular end 36 of the trip member 35 will freely 55 pass the end 50 of the automatic stop latch 18 leaving the power connection intact, it being understood that when the right angular end 36 is in the dotted line position in which it is shown in Figure 1, upon upward movement of the type bed 12 the right angular end 36 of the trip will

engage the end 50 of the automatic stop latch, rock the bell crank lever and disconnect the power from the press.

5 The device operates in the following manner: With the parts in the position in which they are shown in Figure 1, the type bed and cylinder are moving in opposite directions and the cylinder is rotating. As this operation continues the member 45 will rotate and its curved edge 47 will rock the dog 37 and in turn operate the trip member 35 so that its right angular end 36 will not engage the end 50 of the automatic stop latch 18. When, however, the cylinder for any reason does not rotate, the member 45 will not rotate and consequently as the bed travels up 10 the right angular end 36 of the trip 35 will engage the end 50 of the automatic stop latch 18 and rock the bell crank lever as described to disconnect the power and stop the machine.

15 Connected at one end to a screw as at 55 and 20 at the other end to the bolt 39, there is a coil spring 56 which always acts to return the screw 39 to position against the rear wall 41 of the cut out portion 38 of the dog 37, thus insuring that this rear wall will always engage the screw 39 25 when the dog is rocked downwardly. In some instances, with the power cut off, it may be desirable to rotate the cylinder 11 in the opposite direction. When this happens the member 45 will engage the under side of the dog 37, moving 30 the same to the dotted line position in which it is shown in Figure 4 and permitting the member 45 to move freely by the dog 37.

25 In some instances it may be desirable to render this mechanism inoperative and for this purpose, I provide a spring 60 secured to a lug 61 projecting upwardly from the lug 33 in such a manner that when the right angular end 36 of the trip member 35 is moved upwardly into engagement with the spring, the spring will hold 40 the same at all times out of the path of the end 50 of the automatic latch lever 18.

30 From the foregoing it will be apparent that the present invention provides a new and improved control mechanism for printing presses 45 which will act automatically to stop the machine in case the cylinder in its reciprocating movement is not also rotating.

35 Having thus described the invention, what is claimed as new and what it is desired to secure 50 by Letters Patent of the United States, is:

1. A stop for printing presses of the rotating cylinder type, said stop comprising a power cut-off mechanism, means for tripping said power cut-off mechanism, and means for rendering 55 said power cut-off tripping mechanism ineffective to cut off the power so long as the cylinder is rotating and depending upon non-rotation of the cylinder to render the power cut off effective.

2. A stop for printing presses of the type having a type bed and cylinder movable in opposite directions, a power cut-off mechanism, a trip for said power cut-off mechanism, said trip being carried by the type bed, and rotating means carried by the cylinder for moving said power 65 cut-off trip mechanism to inoperative position upon rotation of the cylinder.

3. A stop for printing presses of the type having a reciprocating type bed and a rotating cylinder comprising a power cut-off mechanism, a 70 power cut-off trip mechanism carried by said reciprocating bed and normally movable thereby in the path of the power cut-off mechanism and means carried by the cylinder and operated thereby for moving said power cut-off trip 75

mechanism out of the path of the power cut-off mechanism.

4. A stop for printing presses of the type having a reciprocating type bed and a rotating cylinder including a power cut-off mechanism, a power cut-off trip mechanism comprising a trip normally positioned to engage the power cut-off mechanism, and a cam carried by the rotating cylinder and rotated thereby to engage and rock said trip to a position where it will clear the power cut-off mechanism.

5. In combination with a printing press, control mechanism including a plate adapted for attachment to the printing press, a bearing carried by said plate, a rocking trip mounted in said bearing and normally positioned to engage a portion of said control mechanism, and means for rocking said trip out of control mechanism engaging position.

6. In a printing press including a reciprocating bed, a rotating cylinder, a power cut-off mechanism, a mechanical control mechanism for operating said power cut-off mechanism including a plate detachably mounted on the printing press, a bearing projecting from said plate, a rocking trip member mounted in said bearing and having a portion normally positioned to engage and trip the power cut-off mechanism, and means for moving said portion to a position to clear the power cut-off mechanism when the cylinder is rotating in proper timed

relation with the movement of the reciprocating bed.

7. In a printing press including a reciprocating bed, a rotating cylinder, a power cut-off mechanism, a mechanical control mechanism including a plate detachably mounted on said printing press, a bearing projecting from said plate, a rocking trip member mounted in said bearing and having a portion normally positioned to engage and trip the power cut-off mechanism, and means for moving said portion out of position to engage the power cut-off mechanism when the cylinder is rotating in proper timed relation with the movement of the reciprocating bed, said last mentioned means being carried by the rotating cylinder.

8. In a printing press including a reciprocating bed, a rotating cylinder, a power cut-off mechanism, a mechanical control mechanism including a plate detachably mounted on said printing press, a bearing projecting from said plate, a rocking trip member mounted in said bearing and having a portion normally positioned to engage and trip the power cut-off mechanism, and means for moving said portion out of position to engage the power cut-off mechanism when the cylinder is rotating in proper timed relation with the movement of the reciprocating bed, said last mentioned means comprising a cam carried by the rotating cylinder.

CHARLES GRILLO.
